United States Patent Office

Des. 213,376
Patented Feb. 25, 1969

213,376

ARTIST'S EASEL

Harry J. Hermalin, Los Angeles, Calif., assignor of one-third each to Alfonso T. Atwaters, Hollywood, Calif., and Jam A. Judie, Hollywood, Calif.

Filed June 11, 1968, Ser. No. 12,296

Term of patent 14 years

U.S. Cl. D29—20
Int. Cl. D6—01; D19—07

FIGURE 5 is a side elevation view thereof in another position as seen from the same aspect as FIGURE 4; and

I claim:

The ornamental design for an artist's easel, substantially as shown.

UNITED STATES PATENT OFFICE
CERTIFICATE OF CORRECTION

Design No. 213,376

February 25, 1969

Harry J. Hermalin

It is certified that error appears in the above identified patent and that said Letters Patent are hereby corrected as shown below:

In the grant, lines 2 and 3, "assignor of one-third each to Alfonso T. Atwaters, of Hollywood, California, and Jam A. Judie" should read -- assignor of one-third to James A. Judie --; line 14, "Alfonso T. Atwaters, and Jam A. Judie" should read -- and James A. Judie --. In the heading to the drawings and printed specification, lines 3 to 5, "assignor of one-third each to Alfonso T. Atwaters, Hollywood, Calif., and Jam A. Judie" should read -- assignor of one-third to James A. Judie --.

Signed and sealed this 31st day of March 1970.
